FURNITURE CHEST

Richard G. Barr, Watchung, N.J., assignor to Thomasville Furniture Industries, Inc., Thomasville, N.C., a corporation of North Carolina

Filed Oct. 11, 1966, Ser. No. 4,240

Term of patent 14 years

(Cl. D33—6)

Fig. 1

Fig. 2

FIGURE 1 is a front elevation of the furniture chest embodying the new design,

FIGURE 2 is a side elevation of the furniture chest, embodying the new design.

The essential features of my design reside in the configuration of the leg members and the top edge moulding strip shown in full lines in the drawing. The side of the chest not shown is like the side shown while the top and back are conventional.

I claim:

The ornamental design for a furniture chest, as shown and described.
